Inventor.

FREDERICK COOK

By Frederick C. Bromley
Attorney.

UNITED STATES PATENT OFFICE

FREDERICK COOK, OF HOLLAND CENTRE, ONTARIO, CANADA

WRENCH

Application filed April 17, 1929, Serial No. 355,921, and in Canada September 14, 1928.

The invention relates to improvements in wrenches as described in the present specification and shown in the accompanying drawings which form part of the same.

5 The invention comprehends a simple and serviceable wrench the salient features of which reside in the facility with which it may be adjusted to the article to be turned.

10 The invention consists essentially of a wrench having a long rigid shank terminating in a handle at one end and a rigid jaw at the other end. A slide is attached to the shank and pivotally carries a movable jaw bearing one or more teeth for engagement

15 with a series of teeth on the shank with which it is normally held in engagement by means of a spring, preferably carried around a stem that is connected to a movable jaw and has a button by which it may be depressed to

20 release the jaw for opening purposes.

Referring to the drawings, Figure 1 is a side elevation of the wrench.

Figure 2 is a view of the back thereof.

Figure 3 is a side elevation of the head end 25 of the wrench depicting the movable jaw away from the shank in order to disengage its teeth.

Figure 4 is a cross section taken on the line 4—4 of Figure 1.

30 Like numerals of reference indicate corresponding parts in each of the figures throughout the drawings.

In the drawings, the reference numeral 5 generally indicates the shank which consists 35 of a long bar-like member having the customary handle 6 at one end and a rigid jaw 7 at the other end. Teeth 8 are arranged longitudinally on the shank adjacent to the jaw 7 and extend therefrom for a suitable distance depending upon the extent to which it is desired to open the wrench. 9 is a slide fitted to the shank by means of a T-shaped projection 10 which fits in a correspondingly shaped slot or opening 11 provided in the shank 5. By this construction the slide may 40 be moved to and away from the rigid jaw 7.

12 is the movable jaw which is swivelly connected to the slide 9 as at 13, the swivel preferably being composed of a knob 14 integral with or secured to the jaw and en-

gaged in an opening 15 provided in the slide. This connection permits of the jaw being swung away from the shank as depicted in Figure 3.

16 are teeth arranged on the movable jaw 55 for engagement with the teeth 8 on the shank which teeth may vary in number and are preferably disposed remotely from the pivotal point in order not to obstruct the free movement thereof. These teeth are shaped 60 to preclude opening movement of the jaw but do not obstruct its inward movement towards the fixed jaw. 17 is a stem pivotally attached at 18 to the movable jaw and projects through a slot 19 in the shank 5. The 65 projecting end of the stem carries a rigid button 20 and intermediate of button and shank is an encircling compression coil spring 21 seated against a washer 22 at one end and at the other end against said button. This 70 spring serves to normally retain the jaw in a locked position on the shank through the medium of its teeth.

To use the wrench it is closed about an 75 object by merely manually sliding the movable jaw inwardly. To release the wrench from the object gripped, the button 20 is manually depressed, thus swinging the movable jaw 12 to disengage its teeth 16 from those of the shank, see Figure 3.

80 What I claim is:—

A wrench of the class described comprising 85 a jaw, a toothed shank rigidly extending therefrom in which the teeth are disposed on the jaw side of the shank immediately adjacent to the said jaw, a slide mounted on the shank for lengthwise movement, a further jaw, teeth integral with the frontal portion thereof for engagement with those of the shank, a knob integral with the rear of the 90 second mentioned jaw and lodged in an opening in the front of the slide to pivotally connect this jaw, and a spring-pressed releasing member for normally retaining the pivotal jaw teeth of the pivoted jaw in engagement 95 with those of the aforesaid shank.

Signed at Holland Centre, Ontario, Canada, this 9th day of April, 1929.
